UNITED STATES PATENT OFFICE.

HERBERT B. BLISS, OF NIAGARA FALLS, NEW YORK.

CONTAINER.

Application filed January 28, 1925. Serial No. 5,203.

This invention relates to a new type of seam can be made by the paper board manufacturer. This container is an end loader shipping case of fibre or corrugated board only in the same sense that the slotted end or equivalent material.

It is the object of the present invention to afford a flush end case of the collapsible tube type which employs an absolute minimum of material and in which the body blank can be stitched by the manufacturer. The container is an end loader. If the container has a tube of greater length than its cross section, the box may be said to be an end loader, but obviously the tube may be of greater cross section than its height, in which case it would be more correct to call it the

Referring to the drawings:

10 Fig. 1 is a perspective of one form of the case.

Fig. 2 is a perspective of another form of the case.

Fig. 3 is a plan view showing how the form shown in Fig. 1 is sealed.

Fig. 4 is a similar plan view relating to the form shown in Fig. 2.

Fig. 5 is a plan view of the blank of the form shown in Fig. 1.

Fig. 7 is a plan view of the end blank of both forms.

25 on similar section lines of Fig. 3.
Figs. 12 to 15 inclusive are sections taken
on similar section lines of Fig. 4.

Fig. 16 is a perspective of the end of the frame shown in Fig. 1.

30 Fig. 17 is a perspective of the end of the
form shown in Fig. 2.

Fig. 18 is a perspective of the collapsible tube of both forms.

The body sheet as shown in Fig. 5 is the same as ordinarily employed in the prevailing type of container—the slotted end container. It comprises four side walls, *a*, *b*, *c* and *d*, together with the manufacturer's seam flap *e*. This can be stitched, as shown in Fig. 18, by the manufacturer to provide a collapsible tube. This is the custom with

a collapsible tube. This is the custom with the slotted end container. However, with the slotted end container, the four flaps on each end of the tube are relatively large and

45 the outer set are intended to be overlapped over the inner set, and each set must be of the same width, for otherwise any variation would result in waste in the blank. The re-

would result in waste in the blank. The result is that considerably more material is used in this slotted end container than is necessary to make the several walls of this

65 six-sided receptacle. It is the object of the present invention to overcome this large waste and yet afford a container, namely, a collapsible tube in which the manufacturer's

seam can be made by the paper board manufacturer. This container is an end loader only in the same sense that the slotted end container is an end loader. If the container has a tube of greater length than its cross section, the box may be said to be an end loader, but obviously the tube may be of greater cross section than its height, in which case, it would be more correct to call it the side loader. 60 65

In place of the large flaps in the slotted container each of the walls of the tube is provided with a short corner flap, a^1 , a^2 , b^1 , b^2 , c^1 , c^2 , d^1 and d^2 . These flaps a^2 , b^2 , c^2 and d^2 can be easily stitched to a plain bottom wall f , such as shown in Fig. 7, as this involves no problem of handling the anvil. 70

However, the difficulty lies in being able to properly seal a case of the kind shown in Figs. 1, 3 and 5. This is accomplished by the arrangements, more clearly portrayed in Figs 3 and 4. For instance, here the four positions of the blade anvil are shown by the roman numerals I, II, III and IV. The top wall g is a plain rectangular piece of material and is shown in Fig. 7. The first thing to do is to stitch this to the collapsible tube. In fact, this first stitching operation might be easily performed by the manufacturer and the case shipped with the cover g stitched in place. This may be stitched to any one of the flaps a^1 , b^1 , c^1 and d^1 . It happens in the drawings to be shown as stitched to b^1 . This flap b^1 will ordinarily have to be turned under the cover g , and stitches 1, 2, 3 and 4 are taken leaving a space between some of the stitches, here shown at the middle, for the insertion of a blade anvil; the stitches 1, 2, 3 and 4 are shown taken by a blade anvil, but obviously they might be made by any other anvil.

After this first narrow flap has been stitched to the cover, the container may be charged or for that matter might be charged before the stitching of the cover *g*. The stitching of the cover to the other flaps *a*¹, *c*¹ and *d*¹ becomes the sealing operation. This is effected by placing the blade anvils in under the cover and the two side narrow flaps *c*¹, and *a*¹ as shown in positions II and III. These flaps *c*¹ and *a*¹ are preferably stitched on the outside of the cover but might be on the inside. Then the anvil is shifted to

IV, and stitches 15 to 19 taken for tying the narrow flap d^1 to the cover g . This corner flap d^1 is preferably put on the outside but might be on the inside.

It is preferable to have all the corner flaps, if possible, on the outside of the cover flaps for practical experience has shown that a fibre container in which the wall abuts into the inside corner of the flaps is much stronger and more durable than one where the creases in the flaps do not enclose the edges of the wall. It is therefore to accomplish this purpose that I have designed the modified structure shown in Figs. 2, 4, and 15 6 of the drawings, and some of the other sectional views.

The structure here is precisely the same except one of the flaps, which happens to be here shown as b^1 , is slotted near one end as 20 at h . This permits the larger portion of this corner flap to be turned out on the outside in place of on the inside as is the case for the first stitched flap in the other form. This makes a stronger case by reason of all the 25 edges of the end walls resting in all the creases except for a small distance at one corner. The short flap, as is seen in Figs. 2 and 4, is turned in. This permits the anvil to be inserted for the final stitching operation, through the opening permitted by this turned in flap section. This box can be 30 stitched in precisely the same way as the stitching shown in Fig. 3, but I prefer to show here the stitching running continuously 35 around as this permits more ease in manipulating the anvil in the final stitching operation, permitted by the small turned-in flap section.

I am aware that the three-blank flush-end 40 shipping case per se is not new; it is shown in a large number of my prior patents and in some of the other prior patents, but these flush-end cases heretofore designed are all side loaders as opposed to what may be conveniently called an end loader. That is, the 45 body blank itself was not used as a body tube but the body blank affords the cover flaps which cover up the opening through which the case is charged. This has been a necessary detail of the three-blank flush-end case 50 heretofore designed. In the present case the body blank must be stitched into a tube before the case is packed. In the previously existing flush-end cases the body blank can 55 only be stitched into a tube as part of the final sealing operation. This is an essential difference not only in structure but in handling these boxes.

My container is built entirely of fibre 60 board, corrugated board, straw board, or equivalent material, and requires no frames

of wood or other material to obstruct the corners of the case either outside or in.

What I claim is:

1. A new container, comprising a body 65 blank of four walls united together in a collapsible tube, a closure for the bottom of the tube, the walls at the top of the tube being provided with narrow sealing flaps, and a separate top panel sewed to the turned in 70 sealing flaps by stitching some of the flaps to the panel and leaving an unstitched portion through which a blade anvil is inserted to complete the sealing by stitching of the remaining flap or flaps. 75

2. A new container, comprising a body blank of four walls provided with a manufacturer's seam on one end stitched to the opposite end of the blank to form the same into a collapsible tube, a closure for the bottom of the tube, the walls of the body blank being provided with sealing flaps, and a separate top panel first stitched to one sealing flap and then stitched to the remaining sealing flaps by an anvil which in completing 80 the stitching operation passes between one of the previously stitched flaps and a portion of the top panel. 85

3. The method of setting up and sealing a container, formed by a creased body blank 90 forming four walls and four sealing flaps, and a separate top panel, which method comprises forming the body blank into a tube, applying a closure to the bottom, stitching the top panel to one flap, then stitching the 95 other two flaps, and in one of these operations leaving a space for the subsequent insertion of a blade anvil, and finally completing the stitching of the remaining flap by inserting the anvil through said unstitched portion. 100

4. The method of making and sealing a container, which comprises creasing and cutting a blank to form four aligned side walls and a manufacturer's seam flap at one end and four flaps at each side of the blank, the ones at one side being narrow, the fastening of the manufacturer's seam flap to the opposite end of the case to make a collapsible tube, the applying and fastening a closure 105 to one end of the tube, and sealing the case by turning in the narrow flaps at the opposite end of the tube in connection with the application of a separate top panel and the stitching said narrow flaps to the top panel 110 and concluding the final stitching by a blade anvil slipped in between parts of the top closure along a side of the top panel which has already been stitched. 115

In testimony whereof I have affixed my 120 signature.

HERBERT R. BLISS.
